ELECTRICAL DISCHARGE DEVICE

Johannes Gijsbertus Wilhelm Mulder, Johannes Bruijnes, and Johannes Hendrikus Josephus Maartens, Eindhoven, Netherlands, assignors to N. V. Philips Gloeilampenfabriken, Eindhoven, Netherlands

Application November 28, 1932, Serial No. 644,724
In Germany December 9, 1931

6 Claims. (Cl. 250—27.5)

The present invention relates to electrical discharge devices and more particularly to a novel anode construction for discharge tubes.

In certain types of discharge devices, for instance in heavy duty gas-filled rectifying tubes with thermionic cathodes, the anode assumes during operation a high temperature, which for instance, in gas-filled rectifier tubes is primarily due to its bombardment by the ions. Such overheating of the anode is objectionable as it adversely affects the operating characteristics and life of the tube. To prevent such overheating of the anode various means have been suggested in the past, none of which however has been quite successful.

One way of reducing the anode temperature is by increasing the size of the anode, but this correspondingly increases the weight of the anode. A heavier anode not only requires heavier supports but is specially objectionable in case of glass containers as it increases the load to be carried by the seal and the vitreous envelope of the tube. For instance an otherwise very advantageous seal and support construction, consisting of a chrome-iron disc sealed to one end of the vitreous container and supporting the anode by means of an intermediate rod is unsuitable for heavy anodes as the seal is liable to crack under the weight and momentum of the anode.

It has also been proposed to increase the cooling surface of the anode by means of corrugations provided thereon. However, this gives rise to undesired electron emission from the anode especially at the sharp edges of the corrugations.

It has also been suggested to lighten the anode by means of open cavities provided, for instance, on its side turned away from the cathode. Such construction, however, gives rise to a glow discharge in the cavity, with consequent back discharge between the anode and the cathode.

The present invention provides a novel and simple construction which permits the anode to be provided with a large cooling area without producing the disadvantages of large weight, undesired electron emission, back discharge, etc.

According to the invention the anode is provided with a large and preferably smooth outside area and the anode is lightened by providing it with one or more interior cavities which are fully enclosed and thus are not in communication with the discharge space or with parts outside the tube.

The thickness of the walls of such a hollow anode may be reduced to such extent as is safe

for mechanical considerations, and thus a very light, large area anode can be obtained. As the cavity is closed, the electrical conditions prevailing therein have no disturbing influences on the discharge of the tube.

The invention can be applied to anodes consisting of non-metallic materials, for instance, graphite and carbon, which are specially adapted for gas-filled rectifier tubes, as well as to metal anodes.

The invention will be more fully described in connection with the accompanying drawing forming part of this specification which shows as examples specific embodiments of my invention and in which:

Figure 1 is a longitudinal section of a rectifying tube embodying an anode construction according to our invention.

Fig. 2 is a sectional elevation of a modified anode construction according to our invention.

Figure 3 is a side view, partly in section, of a three electrode discharge tube, comprising a still further embodiment of an anode according to our invention.

Referring to Figure 1 there is shown a rectifying tube comprising a vitreous envelope 1 having a reentrant portion carrying a stem 2 on which is supported a filamentary cathode 3, the two ends of which are connected to lead-in wires 8 and 9. The anode is supported by a chrome-iron disc 4 sealed in the opposite end of the envelope 1 and is carried by a suitable metal rod 10 which may be integral with the disc 4 or may be welded, soldered or otherwise secured thereto. The stem 10 carries a cylindrical carbon or graphite block 5 which is provided with internal threads 12. A threaded carbon plug 6 is tightly screwed in the block 5 to engage its threads 12 and thereby completely closes the cavity 11.

It should be well understood that the cavity 11 can take up the major portion of the block 5, the walls of which can be reduced to such extent that their thickness is merely determined by the requirement of mechanical strength. It is obvious that a very large effective anode-area 45 may be obtained with a comparatively low weight of the anode.

Instead of providing a threaded joint between the block 5 and the plug 6, a suitable tight fit may otherwise be obtained, for instance, by pressing the plug 6 into the block 5.

The incandescent cathode is preferably provided with a high electron emitting surface, for instance, an earth oxide layer, and an indirectly heated cathode may be used instead of the di-

rectly heated cathode shown in the drawing. As a rule there is also provided a gas filling, for instance, mercury vapor or a rare gas or a combination of both.

5 Constructions as shown in Figs. 1 and 2 have been found especially advantageous in gas-filled thermionic rectifier tubes for currents of 20 amps. and more and for voltages up to 100,000 volts and more. In such tubes the gas is preferably argon of pressure of some microns to several mm. The anode is preferably of carbon or graphite or of a refractory metal as zirconium carbonized at its surface. An anode as shown in these figures may have for instance 10 a height of 5 cm. and a diameter of 3 cm. In this case the cavity has a depth of about 2 cm. and a diameter of about .2 cm.

Figure 2 shows a modification of the anode construction in which the plug 6' is provided 20 with a flange 7 which when the plug is screwed in the block 5 abuts with its upper face against the free end face 13 of the block. The two co-operating faces are preferably machined to provide for a tight fit.

25 The block and the plug may be made of the same or of different materials.

Our invention can be also applied to tubes having more than two electrodes. For instance in Fig. 3 there is shown a tube embodying our 30 invention in which a vitreous container 21 is provided with a stem 22 which carries by means of proper supports a cathode 23, a heater 24 for the indirect heating of the cathode and disposed within the cathode, a grid 27 surrounding the cathode and an anode 25 surrounding the 35 grid. The anode 25 is shown as formed of a hollow metal ring preferably of a refractory metal. The ring 25 can be formed, for instance, by joining a two part casting or it may be made 40 of sheet metal formed into proper shape and welded together to form a closed hollow ring member.

While cylindrically shaped anodes, as shown in Figs. 1 to 3 provide as a rule for the most 45 compact construction my invention can be applied to anodes having other shapes, or instead of a single cavity a plurality of cavities may be provided, each being closed by a plug or otherwise. Various other modifications may 50 suggest themselves and we do not wish to be limited to the examples shown and described, but desire the appended claims to be construed as broadly as permissible in view of the prior art.

55 In the claims the term carbon shall include also graphite and other carbon modifications adapted to serve as anode material.

What we claim is:

1. A rectifier tube for currents of 20 amperes 60 or more, comprising an envelope and a gaseous filling therein, a thermionic oxide cathode and a cooperating anode, a discharge space being formed between said anode and cathode, said anode having a cylindrical shape and a large 65 surface area and being provided with a bore which substantially reduces the weight of the anode, said bore being void of non-gaseous matter and being closed by a plug member at its end opposing the cathode.

2. A rectifier tube comprising an envelope and a gaseous filling therein, a cathode and a cooperating anode, a discharge space being formed between said anode and cathode, said anode having a cylindrical shape of large surface area, 5 and having an internal cavity to substantially reduce the weight of said anode, said cavity being entirely closed and void of non-gaseous matter, a chrome-iron member sealed at one end of said envelope, and a support secured to said 10 chrome-iron member to carry said anode and to serve as an electrical connector therefor.

3. A discharge tube comprising a vitreous envelope, a gaseous filling therein, a cathode and a carbon anode disposed within said envelope 15 and forming a discharge path, said anode having a large active surface area and being provided with a large internal cavity to substantially lessen its weight, said cavity being completely closed from the discharge path and being 20 void of all non-gaseous matter, a metal support member hermetically sealed to said envelope, and means exclusively supporting said anode from said member.

4. A rectifier tube for currents of 20 amperes 25 and more, comprising a vitreous envelope and a gaseous filling therein, a thermionic oxide cathode, a cylindrical anode body having a large surface area and being provided with a closed 30 internal cavity to lessen its weight, and supporting means for said anode body comprising a conductor sealed to the vitreous envelope, said anode body and said supporting means being exclusively supported by the seal between said conductor and said envelope.

35 5. A discharge tube comprising a vitreous envelope, an anode and a cathode disposed therein to form a discharge space, said anode having a large surface area and being provided with an internal cavity to substantially lessen its weight, 40 said cavity being closed from the space within the envelope and being void of non-gaseous matter, and means supporting said anode in non-contacting spacial relationship with said envelope, said means being sealed to said vitreous envelope and being exclusively supported by the seal.

45 6. A discharge tube comprising a vitreous envelope having a gaseous filling therein, a cathode and a carbon anode disposed within said envelope 50 and forming a discharge space, said anode having a large surface area and being provided with a large internal cavity to substantially lessen its weight, said cavity being completely closed from the discharge space and being void 55 of non-gaseous matter, a metal member hermetically sealed to said vitreous envelope, and means supporting said anode from said metal member, said anode, supporting means and metal member being exclusively supported by the seal between said metal member and said envelope.
